FUSIBLE PROTECTIVE DEVICE FOR
ELECTRIC CIRCUITS

James A. McEntee, Newburyport, Mass., assignor to The Chase-Shawmut Company, Newburyport, Mass., a corporation of Massachusetts

Application January 22, 1936, Serial No. 60,239

31 Claims. (CL. 200—123)

This invention relates to fusible protective device for electric circuits.

It is common practice to protect electric circuits and the apparatus therein against damage due to overloads by fuses which are in the series with the circuit and are adapted to blow when traversed by a current in substantial excess of their rated continuous carrying capacity. For circuits of moderate current carrying capacity, as say up to and including 30 amperes, the fuses are commonly of the screw plug type. Electric circuits, and many pieces of apparatus operated from the circuits, are able to carry a moderate overload current for a considerable period of time without damage; and in the operation of many pieces of apparatus a considerably higher than normal current is demanded for a short period of time. For instance, an electric motor that is adapted to be connected directly to the line without the use of a starting impedance draws for a second or so or until the motor comes up to normal speed, a starting current that may be from five to ten times in excess of its normal full load running current. An electric fuse and particularly one of the plug type, having a capacity suited to the normal current, ordinarily is unable to carry the momentary overload and thus blows and interrupts the circuit needlessly.

Hence an object of the present invention is the provision of an improved form of a fusible protective device and particularly one of the screw plug characterized by its ability to carry a current that is considerably in excess of its normal rated current for a substantial period of time sufficient to permit excessive current momentarily to be supplied to the circuit and the apparatus therein and yet to operate to interrupt the circuit if excessive current flow persists for an unusual time and also if the normal current is exceeded for a longer time.

A further object of the invention is the provision of an improved form of fusible protective device having means providing for the delayed interruption of the circuit when traversed by a moderate overload current and the quicker or instant interruption of the circuit when traversed by a short-circuit current.

The fusible protective device embodying the present invention includes a normally solid mass of readily fusible metal adapted to be heated to the fusing point by an electric resistance element and when solid retaining therein the spring tensioned end of a movable conducting member and when fused releasing its hold upon the conducting member, thereby permitting the spring to

withdraw the end of the member from engagement with the fused mass and thereby interrupt the circuit.

An object of the present invention is the provision of novel means for holding the fusible metal mass, the holding means being a part of the heating element.

A yet further object is the provision of holding means for the fusible mass wherein the heating element is a resistance conductor wound in a helix, the fusible mass being contained in one end of the helix by direct engagement with the convolutions thereof.

Another object of the invention is the provision of a fusible protective device of the type above described having a construction wherein the operative elements can be contained within a screw plug body the dimensions of which, and particularly the length of which, does not exceed the dimensions of the ordinary plug type of fuse so that the device can go in any receptacle and in any installation having a plug fuse, to replace the fuse.

A further object of the invention is the provision of a fusible protective device of the screw plug type having a novel form of spring for moving the conductor out of the fused fusible mass whereby a relatively great separation is provided between the conductor and the metal mass for a smaller movement of the spring and also wherein the length of the device can be kept down. Another object of the invention is the provision of a fusible protective device wherein a bow spring is utilized to withdraw the conductor from the fused metal mass, the bow spring extending transversely of the enclosure of the casing of the device and being engaged at about its mid point by the conductor, this arrangement permitting an enclosing casing of short length and permitting a long circuit interrupting gap.

Another object is generally to improve the construction and operation of fusible protective devices for electric circuits.

Fig. 1 is a side elevation of the fusible protective device embodying the present invention.

Fig. 2 is a sectional elevation of the device of Fig. 1 taken along line 2—2 of Fig. 1.

Fig. 3 is a plan view of the device of Fig. 1, the cap and transparent window being removed.

Fig. 4 is a section taken along the line 4—4 of Fig. 2.

Fig. 5 is a sectional detail similar to Fig. 4 but illustrating the operated position of the parts.

Fig. 6 is a sectional detail taken along line 6—6 of Fig. 5.

Fig. 7 is a view similar to Fig. 2 but illustrating a modified construction of heating element.

The fusible protective device embodying the present invention comprises in the form herein shown of a generally cylindrical casing or body 10 composed of suitable insulating material, as porcelain, having external screw-threads 12 on the lower circumferential portion thereof on which an externally and internally screw-threaded metal terminal shell 14 is screw-threaded. The body at the bottom has a forwardly projecting boss 16 in which a center contact 18 is fixed, the stem or shank 20 of the center contact having an internal recess 22.

15 The plug body is provided with an internal open-top chamber 24 in which the operative parts of the device are located. The top of the body is provided with a peripherally outstanding flange 26. An electrically insulating transparent disc 28 of suitable material, as mica, overlies the top of the body and is seated upon the flange 26 and constitutes a closure for the open end of the chamber 24. A metal disc-retaining cap 30 has its top wall 32 overlying and seated upon the transparent disc 28 and its side wall 34 engaged with the outer face of the flange 26 and the end of the side wall turned in under the flange and thereby permanently retained tightly engaged with the plug body. The top wall 32 of the cap 30 is provided with an opening or window 36 through which a view of the interior of the plug chamber can be had. The plug body so far described is essentially the body of a plug type of fuse and has the same dimensions.

35 A combined holder and heating element for a mass of readily fusible metal is located in the bottom part of the chamber 24. Said holder and heating element comprises a helix 38 of resistance wire 40, the lower end 42 of the resistance wire being extended parallel with the axis of the helix and located in the recess 22 of the shank of the end cap where it is permanently retained by a mass of solder having a melting point sufficiently high to remain solid at any 45 temperature sufficient to melt the readily fusible metal and cause the operation of the device. The uppermost two or three turns 46 of the helix are in substantial contact or at least are sufficiently close to one another to form a cup to 50 retain a mass 48 of readily fusible metal. The cup is provided with a bottom by a plate 50 of suitable heat resistant sheet material, as mica, for instance, which is inserted between and is gripped by the convolutions under the fusible mass. The convolutions below the cup are separated and constitute a heating coil which when traversed by sufficient current heats the readily fusible metal mass 48 in the cup and ultimately causes it to melt or fuse.

60 While the bottom plate 50, as above described, is intended to be a permanent part of the cup, its presence in the completed device is not essential. The plate may be retained in place while the molten metal is poured into the cup and 65 until the metal mass has solidified. It can then be removed. Such a construction is illustrated in Fig. 7. For this purpose the plate can be of mica, aluminum or other sheet material not harmed by the heat of the molten metal mass or adapted to bond therewith.

70 The fusible metal mass is normally connected to the terminal shell 14 through a flexible conducting strip 52 which preferably is composed of copper although it can be composed of fuse link material, usually zinc. The inner end 54 of

75 the strip is imbedded in the normally solid metal mass 48 and is thereby held in electrical and mechanical engagement with the metal mass and is anchored thereby. The outer end 56 of the strip is located in a channel 58 formed in the wall of the body 10 and is imbedded in a mass 60 of solder by which it is connected electrically with the terminal shell 14. The strip is thus of looped or inverted U formation. The strip is under spring tension acting in such manner as 10 to constantly act upon the inner end 54 of the strip to pull it upwardly out of engagement with the fusible metal mass 48 when said mass becomes fused.

15 The spring tension is provided with a bow 15 spring 62 consisting of a normally straight helix of spring wire wound in close convolutions. The spring helix is extended transversely across the chamber 24 of the plug body under the conducting strip 52, and the ends of the spring helix 20 are received in notches 64 formed in the side wall of the plug body immediately under the transparent cover 28. Barriers 66 integral with the plug body traverse the ends of the notches to isolate the ends of the spring helix from the 25 metal cap 30. The diameter of the spring helix and the depth of the notches 64, however, preferably is such that the helix projects slightly above the tops of the notches so that the mica disc 28 is pressed firmly thereagainst by the 30 metal cap whereby to grip the ends of the spring helix between the mica disc and the bottoms of the slots so as to prevent endwise movements of the spring.

35 The conducting strip 52 is looped over the middle part of the spring helix and the length of the strip is such that in the normal condition of the device the spring helix is bowed downwardly by a substantial amount as indicated in Figs. 2 and 4, thereby placing the conducting strip 40 under a tension in a direction to withdraw the inner end of the strip out of the fusible metal mass.

45 In the assembly of the device the following procedure is convenient. The ends of the conducting strip are secured to the solder masses 48 and 60 with the strip forming an upstanding loop, as shown. A curved wire or needle is then run through the initially straight spring 62, thereby forming it into the bow shape illustrated. The spring on the needle is then passed under the looped strip 52 and the ends of the spring located in the notches 64. The needle is then withdrawn out of the spring and the spring flexes upwardly somewhat and applies tension 50 on the strip 52; the ends of the spring bearing downwardly on the bottoms of the notches and projecting upwardly partly above the top face of the plug body 10. The mica disc 28 and end cap 30 are then applied, bending the upstanding spring ends downwardly and clamping them in place. The clamping action is desirable for preventing endwise movement of the spring especially if the walls 66 of the notches are omitted but is not necessary merely to retain the spring 55 ends in the notches.

60 Under normal conditions of service, where the device is traversed by not more than the current which it can carry continuously the parts remain in the aforesaid relation. When, however, 65 the device is subjected for a sufficient period of time to an excessive current the heat generated by the heating element 38 raises the temperature of the readily fusible metal mass to the melting point thereof. The metal mass thus 70

75

becomes fluid and no longer can retain its grip on the inner end of the conducting strip 52. The inner end of the strip is thereupon pulled rapidly upward out of the fusible mass by the 5 tension of the bow spring 62, thereby interrupting the circuit, the bow spring usually assuming a straight horizontal position as illustrated in Fig. 5.

Due to the arrangement of the spring under 10 and in engagement with the looped portion of the conducting strip and to the fact that there is a relative movement between the strip and the spring in the direction of the length of the strip, the upward movement of the inner end of the 15 conducting strip is twice that of the upward movement of the spring, per se. Due also to the inherent rigidity of the free end of the conducting strip said end is moved upwardly into a position where it lies against the inner face of 20 the mica disc 28 as illustrated in Fig. 6. Thus a very large distance of separation between the strip and the fusible metal mass is attained without the necessity for a long length of enclosing casing.

25 The conducting strip 52 is preferably provided with a more readily fusible portion, or fusing zone by having a part of reduced cross-section as made by the perforation 68 located in the inner end of the conducting strip in a position 30 to be out of the mass of readily fusible metal when the device is in service condition. The strip is thus adapted to blow or fuse instantly when traversed by short-circuit current. Since the conducting strip is under spring tension 35 throughout its length the separated ends of the blown strip are rapidly and widely separated by the spring 62 in the manner previously described.

For some purposes the perforation 68 is not 40 needed especially when the strip 52 is a thin copper strip which has relatively high conductivity and little mass and on short circuit currents can vaporize more or less completely without the generation of harmful gas pressures within the 45 enclosing casing. For currents of lesser magnitude but still sufficient to fuse the strip before the readily fusible metal melts, the strip will fuse at its portion of highest temperature, usually between the spring 62 and the mass of fusible metal 48, which portion is thus the equivalent 50 of the more readily fusible portion provided by the perforation 68.

I claim:

1. A fusible protective device comprising a 55 fusible mass, heating means for melting said mass, a fusible conductor having an end engaged with and anchored by said mass and adapted to be released upon the fusing of said mass, terminals, said conductor, heating means and fusible mass being in series with said terminals, said conductor having a part adapted to fuse when traversed by a dangerous current, and spring means operatively excluded from the circuit between said terminals tensioning said conductor at said fusible mass and also at said fusing part.

2. A fusible protective device comprising a 60 fusible mass, heating means therefor, a fusible conductor having one anchored end and its other end engaged with and anchored by said mass, terminals between which said mass, heating means and conductor are connected in series, said conductor having a fusing section, and spring means operatively excluded from the circuit between said terminals engaged with and acting on

said conductor intermediate its ends in a direction that tensions said conductor at said fusible mass and also at said fusing section.

3. In a fusible protective device having a fusible mass, a conductor engaged with and anchored by said fusible mass, and spring means to withdraw said conductor from the molten fusible mass, the combination therewith of a holder for the fusible mass comprising a helix having convolutions directly engaged with and within which the fusible mass is disposed.

4. In a fusible protective device having a fusible mass, a conductor engaged with and anchored by said fusible mass, spring means to withdraw said conductor from the molten fusible mass, the combination therewith of a holder for the fusible mass comprising a helix having close convolutions directly engaged with and within which the fusible mass is disposed.

5. In a fusible protective device having a fusible mass, a conductor engaged with and anchored by said fusible mass, spring means to withdraw said conductor from the molten fusible mass, the combination therewith of a holder for the fusible mass comprising a helix having close convolutions directly engaged with and within which the fusible mass is disposed, and a bottom closure member traversing the helix under said fusible mass and located between convolutions of the helix.

6. In a fusible protective device having a fusible mass, a conductor engaged with and anchored by said fusible mass, and spring means to withdraw said conductor from the molten fusible mass, the combination therewith of a holder for the fusible mass comprising a helix having close convolutions directly engaged with and within which the fusible mass is disposed, and a bottom closure member traversing the helix under said fusible mass and located between the convolutions of the helix, the convolutions on opposite sides of said closure member being in pressure engagement therewith.

7. In a fusible protective device having a fusible mass, a conductor engaged with and anchored by said fusible mass, and spring means to withdraw said conductor from the molten fusible mass, the combination therewith of an electric heating coil for said fusible mass having some of its convolutions surrounding and directly engaged with said fusible mass and forming a retaining cup therefor.

8. In a fusible protective device having a fusible mass, a conductor engaged with and anchored by said fusible mass, and spring means to withdraw said conductor from the molten fusible mass, the combination therewith of a holder and electric heating element for said fusible mass comprising a resistance helix having said fusible mass retained therein by direct engagement with convolutions of said helix which form a retaining cup for said fusible mass.

9. In a fusible protective device having a fusible mass, a conductor engaged with and anchored by said fusible mass, and spring means to withdraw said conductor from the molten fusible mass, the combination therewith of a holder and electric heating element for said fusible mass comprising a resistance helix having a series of open convolutions and a series of close convolutions, said fusible mass being contained within and engaged with said close convolutions.

10. In a fusible protective device having a fusible mass, a conductor engaged with and anchored by said fusible mass, spring means to withdraw

said conductor from the molten fusible mass, the combination therewith of a holder and electric heating element for said fusible mass comprising a resistance helix having a series of open convolutions and a series of close convolutions, said fusible mass being contained within and engaged with said close convolutions, and a closure member traversing said helix under said fusible mass.

11. A fusible protective device comprising an electric resistance helix, a fusible mass contained in one end of said helix and retained therein by engagement with convolutions thereof, an electric conductor having a part engaged with and anchored by said fusible mass, and spring means for withdrawing said conductor from said fusible mass.

12. A fusible protective device comprising an electric resistance helix, a fusible mass in one end of said helix and retained therein by engagement with convolutions thereof, an electric conductor having a part engaged with and anchored by said fusible mass, spring means for withdrawing said conductor from said fusible mass, said helix having close convolutions at one end surrounding and directly engaging said fusible mass, and a closure plate traversing said helix under said fusible mass.

13. A fusible protective device comprising a plug body having a center contact, a screw-threaded shell and an internal chamber, a heating element comprising a resistance helix in said chamber having an end connected with said center contact, a fusible mass retained in the other end of said helix by direct engagement with convolutions thereof, a conductor having one end engaged with and anchored by said fusible mass and its other end connected with said shell, and spring means for withdrawing said conductor from said fusible mass.

14. A fusible protective device comprising a fusible mass, a conductor forming a part of the circuit through said device engaged with and anchored by said fusible mass, spring means for withdrawing said conductor from said fusible mass, and means for supporting said spring means for flexure transversely of its length; said spring means bearing on and disposed with its length transversely of the length of said conductor.

15. A fusible protective device comprising a fusible mass, a conductor forming a part of the circuit through said device engaged with and anchored by said fusible mass, and means including a bow spring acting on said conductor for withdrawing it from said fusible mass.

16. A fusible protective device comprising a fusible mass, a conductor engaged with and anchored by said fusible mass, and means having a determined distance of action for withdrawing said conductor a greater distance from said fusible mass.

17. A fusible protective device comprising a fusible mass, a conductor forming a part of the circuit through said device engaged with and anchored by said fusible mass, and a bow spring for withdrawing said conductor from said fusible mass, said bow spring being disposed cross-wise of said conductor in engagement therewith.

18. A fusible protective device comprising a fusible mass, a conductor having a fixed end and an end anchored by said fusible mass, and a bow spring disposed cross-wise of said conductor and acting thereon intermediate the ends thereof.

19. A fusible protective device comprising a fusible mass, a conductor having a fixed end and

an end anchored by said fusible mass, and a bow spring comprising a spring helix disposed cross-wise of said conductor and acting thereon intermediate the ends thereof.

20. A fusible protective device comprising a fusible mass, a conductor having a fixed end and an end anchored by said fusible mass, a bow spring comprising a spring helix disposed cross-wise of said conductor and acting thereon intermediate the ends thereof, and a support for the ends of said helix.

21. A fusible protective device comprising a fusible mass, a looped conductor having a fixed end and an end anchored by said fusible mass, and a spring helix disposed cross-wise of said conductor in the loop thereof and bearing thereagainst.

22. A fusible protective device comprising a fusible mass, a looped conductor having a fixed end and an end anchored by said fusible mass, a spring having a part disposed cross-wise of said conductor in the loop thereof and bearing thereagainst, and an anchorage for said spring.

23. A fusible protective device comprising an enclosing casing having terminals, a fusible mass connected with one terminal, a conductor connected between said fusible mass and said other terminal, and a spring helix extended cross-wise of and bearing against said conductor between the ends thereof.

24. A fusible protective device comprising a plug body having a center contact and a screw-threaded shell, a fusible mass connected with said center contact, a loop conductor having one end releasably anchored by said fusible mass and its other end connected with said shell, and a spring having a part extended transversely of said conductor and bearing on the loop part thereof.

25. A fusible protective device comprising a plug body having a center contact and a screw-threaded shell, a fusible mass connected with said center contact, a looped conductor having one end releasably anchored by said fusible mass and its other end connected with said shell, and a tensioned spring helix disposed cross-wise of said conductor and bearing on the loop thereof.

26. A fusible protective device comprising a fusible mass, a conductor having a fixed end, and an end releasably anchored by said fusible mass, and spring means having a part extended transversely of and bearing on said conductor and tensioning the entire conductor between its ends.

27. A fusible protective device comprising a casing having a chamber, a spring helix traversing said chamber and having its ends supported by the wall of said chamber, a conductor extended across said helix and bearing thereagainst, and a fusible mass releasably anchoring the end of said conductor.

28. A fusible protective device comprising a casing having a chamber, a center contact and a screw-threaded shell carried by said casing, a spring helix traversing said chamber and having its ends supported by said casing, a conductor having an end connected to said shell and extended across and bearing against said helix, and a fusible mass connected with said center contact and releasably retaining the other end of said conductor.

29. A fusible protective device comprising a casing having an open ended chamber, a transparent insulating member traversing the open end of said chamber, means for retaining said transparent member in place, a center contact at the bottom of said casing, a screw-threaded shell

surrounding said casing, a spring helix extended across said chamber under said transparent member and having its ends supported by said casing, a conductor having an end connected with said shell and extended across and bearing against said helix, and a fusible mass connected with said center contact releasably retaining the other end of said conductor.

30. A fusible protective device comprising a resistance heating element having a supported end and a free end, a fusible mass carried by one end of said element, a terminal connected with the other end of said element, a conductor having one end releasably anchored by said fusible mass and having a fusing part, a second terminal connected

with the other end of said conductor, and spring means exerting tension on said conductor and said fusing part thereof.

31. A fusible protective device comprising an enclosing casing having a window, a fusible mass within said casing, current responsive means for fusing said mass, a flexible conductor engaged with and normally anchored by said mass in a position remote from said window, and means under said conductor for withdrawing said conductor from the fused mass and for flexing it into position displaying the freed end thereof closely adjacent said window.
